UNITED STATES PATENT OFFICE.

RUDOLF WINTZER, OF MILWAUKEE, WISCONSIN, ASSIGNOR TO POWER AND MINING MACHINERY COMPANY, OF NEW YORK, N. Y., A CORPORATION OF NEW JERSEY.

RECIPROCATING ENGINE.

1,037,840.

Specification of Letters Patent. Patented Sept. 3, 1912.

Application filed August 23, 1906. Serial No. 331,796.

To all whom it may concern:

Be it known that I, RUDOLF WINTZER, a subject of the Emperor of Germany, residing at Milwaukee, in the county of Milwaukee and State of Wisconsin, have invented certain new and useful Improvements in Reciprocating Engines, of which the following is a specification, reference being had therein to the accompanying drawing.

10 This invention relates to improvements in reciprocating engines and has for its object the provision of a construction that will obviate certain difficulties encountered in the manufacture and operation of some engines of this type.

As my improvements are especially adapted to internal combustion engines of large size, I have shown in the accompanying drawing an engine of this class.

20 Figure 1 is a vertical longitudinal section through a portion of a double-acting tandem engine embodying my improvements. Fig. 2 is a transverse section on the line 2—2 of Fig. 1. Figs. 3 and 4 are similar sections 25 showing modified forms of the engine. Fig. 5 is a sectional elevation showing still another form of construction. Fig. 6 is a transverse section on the line 6—6 of Fig. 5. Fig. 7 is a cross section through the connecting rod showing an attachment that may 30 be used to connect said rod and cross-head guide when dismantling the engine.

Referring to the details of construction, A indicates the main frame of the engine, 35 B the front cylinder having the removable heads I—I' and being mounted on a supplemental bed frame section (not shown). A piston C works within cylinder B, being mounted upon the piston rod in any desired 40 manner, the front section D of said rod being connected to the cross-head E while the rear section D' is coupled in a well known manner with the rod of the rear cylinder.

The main frame A comprises the up- 45 standing side walls A' A² which are preferably cast hollow as shown, the latter wall A² being provided with a central strengthening rib as shown in Fig. 2. The side walls are connected by the horizontal web 50 or plate a—a' which is supported by a longitudinal web and numerous cross webs, as shown in Figs. 1 and 2. The forward part of the plate a—a' sweeps downward forming a concave section A³ to accommodate the 55 crank and connecting rod. The web a—a'

supports the cross-head E, which is connected by the connecting rod F to the overhanging crank G of the shaft H.

The cross-head E comprises the side plates c—e and the bottom plate or shoe e'. The cross-head is open at the top except at its rear end where the side plates c—e are joined by the circular boss d which receives the front end of the piston rod D. The side plates e—e are bored to receive the pin J. 65

L indicates the cross-head guide which consists of a plate or block with an upper face to receive the bottom part e' of the cross-head. This guide plate L, contrary to the usual practice, is not an integral part of the frame A, but is a separate part secured by bolts l—l to the cross web a—a'. 70

K—K are retaining flanges bolted to the edges of the guide so as to overlap the projecting side edges of the bottom plate a' of the cross head. 75

In the operation of double acting tandem gas engines, it is the common practice to remove the piston of the front cylinder for purposes of inspection, repairs, etc., through the front end of said cylinder. This has made it necessary in most cases to disconnect the connecting rod and cross-head and it also requires that the cross-head guide be disposed low enough to permit the cylinder head to be withdrawn over it, a construction which results in a very high cross-head. 80 Furthermore the cross-head guide, as commonly constructed, being an integral part of the frame is exposed during the work of dismantling and is not infrequently seriously damaged by the dropping of tools or the like by the workmen. It will be readily seen that the construction which I provide 85

obviates all these difficulties for it is only necessary, in order to remove the piston C and its rod D—D', to disconnect the rod from the cross-head and the piston rod of the rear cylinder, remove the retaining bolts l—l and raise the cross-head, guide and connecting rod out of the way as indicated by dotted lines in Fig. 1, all of these parts remaining intact and none of the bearing surfaces being separated. This gives ample clearance for the removal, first of the cylinder head I, and then of the piston and piston rod. Obviously the separable cross head guide may be made as high as desired, and the height of the cross-head be reduced to a minimum. When the parts are raised, 100 105 110

as shown in dotted lines, it is desirable to secure the cross-head guide to the cross-head or connecting rod and for this purpose a clamp O such as shown in Fig. 7, may be used. This clamp consists of a rod O' bent as shown to embrace the connecting rod, a cross plate O^2 with holes to receive the threaded ends of the rod, and nuts O^3 to draw the bent rod and plate together so as to clamp them to the connecting rod. The clamp is shown mounted on the connecting rod in Fig. 7 and in dotted lines in Fig. 1. When the piston of the front cylinder is to be removed the clamp is set close to the front end of the cross head guide and secured thereto by a screw bolt O^4 or the like, the adjacent end of the cross head guide being formed with a tapped hole L' to receive said bolt.

20 My construction has further advantages that pertain more especially to construction or manufacture. With the guide made separable, it is clear that it may be of metal of a quality suitable to its function, that is, 25 it may be made of harder iron than the main frame. Furthermore, in case scraping of the guide surface is necessary or desirable, this may be done more easily if the guide is a separate part than when it is formed integral with the engine frame. Furthermore, the machining of the biggest and heaviest part of the engine, that is the frame, is reduced to a minimum and in addition the cross-head and guide may be 30 assembled before the frame is erected and the time of erection thus reduced.

In Fig. 8, I have shown the modified construction which I prefer to use in the case of engines of extremely large size. 40 Here the engine frame is formed in two parts, separable along a vertical longitudinal plane through the longitudinal web a^6 , which supports the horizontal cross webs or plates a^4-a^5 . The two frame sections 45 are secured together by bolts a^7 , the plates a^4-a^5 being formed with upwardly projecting flanges to receive the top series of these securing bolts. Such a construction as this 50 would be difficult if not impossible of use if the cross head guide were an integral part of the frame. With my construction, however, the difficulty is easily overcome by providing the separable guide L^2 with depending ribs or flanges l^4 , to pass over the 55 up-standing bolted flanges of the frame. The guide L^2 is provided with retaining flanges as in the former construction and is secured to the engine frame by suitable bolts.

In Fig. 4, I show a further modification 60 by which I attain the well-known advantages incident to the bore cross-head guide. In this case the bottom surface l^2 of the guide L^2 is turned from the longitudinal center of the cross-head, and the face l^3 of the engine 65 frame is bored from the same spindle with

which the cylinder flange of the frame is faced. The guide is secured to the frame by bolts l^4 in a manner to hold the guide securely against longitudinal movement, while permitting a slight turning movement or 70 oscillation.

In Figs. 5 and 6, I show still another form of construction which, however, embodies many of the foregoing features of improvement. Here the cross-head E' rests upon a 75 guide beam M . The cross plate a^8 of the engine frame is formed with bosses or elevated parts as a^7-a^7 , upon which the guide beam is bolted. N is a stirrup bolted at $n-n$ to the cross-head and serves to retain the 80 cross-head in proper engagement with the guide.

What I claim is:—

1. In a reciprocating engine, the combination of a frame, a cylinder rigidly secured 85 to said frame, a head for the cylinder removable therefrom without relative movement of the cylinder and frame, a piston in the cylinder, a rod therefor extending through the said removable head, a crank 90 shaft, a connecting rod, a cross head secured to the connecting rod and detachably secured to the piston rod, and a cross head guide detachably mounted on the engine frame adjacent said removable cylinder 95 head, said cross head guide being removable bodily with the cross head from its normal position without separating the connecting rod either from the cross head or the crank shaft, substantially as set forth. 100

2. In a horizontally reciprocating engine, the combination of a frame, a cylinder rigidly secured to the frame, a head for the cylinder removable therefrom without relative movement of the cylinder and frame, a 105 piston in the cylinder, a rod therefor extending through said removable head, a crank shaft, a connecting rod, a cross head uniting the connecting rod and piston rod and detachably secured to the latter, and a 110 cross head guide detachably mounted on the engine frame beneath the cross head and adjacent the said removable cylinder head, said cross-head guide being removable bodily with the cross head from its normal position 115 without separating the connecting rod either from the cross head or the crank shaft, substantially as set forth.

3. In a reciprocating engine, the combination of the engine frame, the connecting rod, 120 the piston rod, the cross-head detachably secured to the piston rod, the cross-head guide detachably secured to the engine frame, and means adapted to secure the connecting rod and the cross-head guide together when said 125 guide is detached from the frame, substantially as set forth.

4. In a reciprocating engine, the combination of the engine frame, the connecting rod, 130 the piston rod, the cross-head detachably se-

cured to the piston rod, the cross-head guide detachably secured to the engine frame, and means adapted to secure the cross-head guide against longitudinal movement relative to the cross-head when said guide is detached from the frame, substantially as set forth.

5. In a reciprocating engine, the combination of the engine frame, the cylinder having a detachable head, the piston, the piston rod passing through said head, the cross-head detachably secured to said rod, and the cross-head guide detachably secured to the engine frame, the engaging surfaces of the 10 guide and frame being cylindrical and concentric with the piston rod, substantially as 15 and for the purpose set forth.

6. In a horizontally reciprocating engine, the combination of a frame, a cylinder rigidly secured to the frame, a head for the cylinder removable therefrom, a piston in the cylinder, a rod therefor extending through said removable head, a crank shaft,

a connecting rod, a cross head uniting the connecting rod and piston rod and detachably secured to the latter, and a cross head guide detachably mounted on the engine frame beneath the cross head and adjacent the said removable cylinder head; the said cross head guide when in position on the 25 frame having its upper guide surface disposed above the horizontal plane of the lower side of the adjacent cylinder head, and said cylinder head being removable, when the cross head guide is detached, without relative movement of the cylinder and frame and while the piston and its rod are in 30 normal position in the cylinder, substantially as set forth.

35 In testimony whereof I affix my signature, 40 in presence of two witnesses.
